US00D840811S

(12) **United States Design Patent** (10) Patent No.: **US D840,811 S**
(45) Date of Patent: **** Feb. 19, 2019**

(54) **CLOSURE**

- (71) Applicant: **Closure Systems International Inc.**,
Lake Forest, IL (US)
- (72) Inventor: **Larry Holmes**, Fishers, IN (US)
- (73) Assignee: **Closure Systems International Inc.**,
Lake Forest, IL (US)
- (**) Term: **15 Years**
- (21) Appl. No.: **29/661,753**
- (22) Filed: **Aug. 30, 2018**

CLAIM

The ornamental design for a closure, as shown and described.

DESCRIPTION

FIG. 1 is a top-perspective view of a closure;
FIG. 2 is a side cross-sectional view of the closure of FIG. 1 taken in the direction of line 2-2;
FIG. 3 is a bottom-perspective view of the closure of FIG. 1;
FIG. 4 is a top plan view of the closure of FIG. 1;
FIG. 5 is a left side elevation view of the closure of FIG. 1;
FIG. 6 is a right side elevation view of the closure of FIG. 1;
FIG. 7 is a front elevation view of the closure of FIG. 1;
FIG. 8 is a back elevation view of the closure of FIG. 1; and,
FIG. 9 is a bottom plan view of the closure of FIG. 1.
The dash-dash broken lines in the drawings depict portions of the closure that form no part of the claimed design.

1 Claim, 4 Drawing Sheets
